SPOON OR SIMILAR ARTICLE

Robert A. Eckersberg, Chicago, Ill., assignor to Eko Products Company, Chicago, Ill., a corporation of Illinois

Filed June 30, 1960, Ser. No. 61,164

Term of patent 14 years

(Cl. D54—12)

Fig. 1 is a front elevational view of a spoon or similar article showing my new design.

Fig. 2 is a side elevational view thereof.

Fig. 3 is an enlarged transverse sectional view taken on line 3—3 of Fig. 1.

I claim:

The ornamental design for a spoon or similar article, as shown.
